US00D978962S

(12) United States Design Patent (10) Patent No.: US D978,962 S
(45) Date of Patent: * Feb. 21, 2023

(54) TYPEFACE

- (71) Applicant: Truist Bank, Charlotte, NC (US)
(72) Inventors: Bianca Berning, Bromley (GB); Rafael Saraiva Soares, Rio de Janeiro (BR)
(73) Assignee: Truist Bank, Charlotte, NC (US)
() Term: 15 Years
(21) Appl. No.: 29/777,752
(22) Filed: Apr. 8, 2021
(51) LOC (14) Cl. 18-03
(52) U.S. Cl. D18/24
(58) Field of Classification Search
USPC D18/24, 26, 27, 28, 29, 30, 31, 32, 33;
101/397, 399
CPC B41B 1/02; G09B 1/04
See application file for complete search history.
